MULTIPURPOSE PLIERS

Alfred Z. Boyajian, Manhattan Beach, Calif., assignor to
The Stanley Works, New Britain, Conn.

Filed Dec. 18, 1970, Ser. No. 26,570

Term of patent 14 years

Int. Cl. D8—05

U.S. Cl. D8—58

FIG. 1

FIG. 2

FIG. 3

FIG. 4

FIG. 5

FIG. 6

FIG. 1 is a perspective view of multipurpose pliers showing the new design;

FIG. 2 is a view of one side thereof;

FIG. 3 is an elevational view of a longitudinal edge thereof, the opposite longitudinal edge being a mirror image thereof;

FIG. 4 is a view of the side opposite that shown in FIG. 2;

FIG. 5 is an elevational view of the handle end thereof; and

FIG. 6 is an elevational view of the jaw end thereof.

I claim:

An ornamental design for multipurpose pliers, as shown and described.
